UNITED STATES PATENT OFFICE.

CHARLES BROWN, OF EMPORIA, KANSAS.

BARBER'S DRESSING-CASE.

SPECIFICATION forming part of Letters Patent No. 391,506, dated October 23, 1888.

Application filed July 16, 1886. Serial No. 208,183. (No model.)

To all whom it may concern:

Be it known that I, CHARLES BROWN, of Emporia, in the county of Lyon and State of Kansas, have invented certain new and useful 5 Improvements in Barbers' Dressing Cases, of which the following is a specification.

My invention relates to certain improvements in barbers' furniture; and it has for its object the construction of a case containing a 10 lavatory apparatus and convenient spaces for holding the various tools and appliances used by barbers.

In the accompanying drawings, Figure 1 represents a front view of my improved case, and 15 Fig. 2 a side or end view thereof with the framing broken away to show the interior. Fig. 3 is a detail perspective view of the razor-case.

A represents an upright case having the 20 base or lower portion, A', and closed at the top by a hinged cover, A".

B is the upper part of the base A', forming a shelf, at each end of which wash basins or 25 bowls b b are provided.

25 Against the rear wall of the upper case, A, is placed a double row of pigeon-holes, C C.

In the center of the case is a mirror, D, upon a hinged door, which conceals a recess of 30 convenient shelves, as indicated in dotted lines in Fig. 1. At each side of this mirror is a row of hooks, E E, upon which brushes and other articles may be hung. Below the spaces containing these hooks I provide the open compartments F.

35 Below the mirror I provide the razor-case G, having a glass front and provided with a series of recesses or pockets, g, in which the razors and shears are placed. This case is provided at its ends with the studs g', which 40 are engaged by the hooks g", secured to the casing by means of springs g", as shown. The razor-case is thus removably secured in place, the springs drawing backward on the hooks and holding them in engagement with the 45 studs, so as to prevent the falling of the case.

Beneath this case the space is utilized for 50 money-drawers H H, between which toilet articles can be placed.

The front of the case is closed by a rolling 55 cover, I, which is attached at its lower end to the drum J. Said drum is provided with a

spring, j, one end of which is attached to the case A. The cover I is provided at its upper end with a spring-lock, K, which engages a suitable staple or other catch when the cover 55 is drawn up over the front of the case. Upon unlocking this lock the spring j will cause the drum J to revolve and the cover I to be drawn down and wound thereon. The cover I is composed of a series of transverse slats flexibly 60 jointed together, and has its side edges working in guideways provided along the sides of the upper portion of the case. When the cover is slid down, it is received within the base portion A' by being wound upon the drum, 55 the end of the cover projecting slightly above the base portion, so as to be caught by the hand.

The small roller L (shown in Fig. 2) acts as a guide for the cover I as it is wound upon the 70 drum J.

In the upper portion of the case A two water-tanks, m m', are located, which contain the water to be supplied to the basins b b. Beneath each of these tanks I provide shelves, 75 upon which lamps may be placed, the flame from which will heat the water in the tanks. These tanks are made smaller at the bottom than at the top, in order that the hot air from the lamps may circulate between them and 80 more effectually heat the water contained therein. The water from these tanks is conveyed to the bowls b b through pipes O O, the upper ends of which enter the bottom of the tanks and are closed by conical plugs P. 85 These plugs are attached to rods Q, which extend upward through the tank and over the back of the case and downward to a point below the level of the shelf B, where they are connected to levers R R, which are fulcrumed 90 about the middle of their length to brackets r and terminate at their front ends in upright thumb-pieces S, which extend up through shelf B.

As will be seen from Fig. 2 of the drawings, 95 if pressure is applied to the thumb-piece S, the rear end of the lever R will rise, carrying upward the rod Q, and causing the conical plug P, attached to said rod, to rise from its seat in the pipe O, when the water will flow through 100 said pipe to the basin b. Upon removing the hand from thumb-piece S the operation is re-

versed and the conical plug restored to its seat in the pipe. The lever R is secured against accidental movement by means of the flat spring T.

5 I claim—

1. The combination, with the casing, of the razor-case having the studs g' at its ends, the hooks engaging said studs, and the springs securing said hooks to the casing, as set forth.

10 2. The combination of the casing, the tanks in the upper portion of the same, the basins in the lower portion of the same, the lamps arranged below the tanks, the pipes O, leading from the tanks to the basins, the levers R, pivoted at an intermediate point of their length and provided at their front ends with the knobs S, the springs T, bearing on the levers in rear of their pivots, and the rods Q, adapted to close the pipes O, and extending up through 15 the tanks and downward in rear of the casing, and having their lower ends pivoted to the rear ends of the levers, substantially as specified.

20 3. In a barber's dressing-case, the case A, in the form of a cabinet and having a base or 25 lower portion, A', which is hollow and forms

a receptacle, and the drum J, contained and concealed within the said receptacle, and the upper portion having a series of pigeon-holes, C, and suitable other receptacles for the tools and appliances used in the trade, and the cover I, composed of a series of transverse slats flexibly jointed together, one end of the cover being connected to the drum J, the side edges thereof working in guideways provided along the sides of the upper portion of the case, and the other end of the cover carrying a lock and working through a slot in the top of the base portion A', the said lock on the cover being adapted to engage the upper part of the case, whereby when the cover is in place the tools, appliances, pigeon-holes, and receptacles in the upper portion of the case are concealed, and when the cover is slid down it is received within the base portion A' by being wound 40 upon the drum J, the end of the cover projecting slightly above the base portion, so as to be caught by the hand, as set forth.

CHARLES BROWN.
